UNITED STATES PATENT OFFICE.

EDWARD E. GREEN, OF SAN FRANCISCO, CALIFORNIA.

DESIGN FOR A STEP-PLATE.

55,605.

Specification for Design.

Patented July 6, 1920.

Application filed October 29, 1919. Serial No. 334,370. Term of patent 14 years.

To all whom it may concern:

Be it known that I, EDWARD E. GREEN, a citizen of the United States, residing at the city and county of San Francisco, State of California, have invented a new, original, and ornamental Design for a Step-Plate, of which the following is a specification, reference being had to the accompanying drawing, forming part thereof.

The illustration is a plan view showing my new design.

What I claim and desire to secure by Letters Patent is:—

The ornamental design for a step plate as shown.

EDWARD E. GREEN.
